(57) **CLAIM**

The ornamental design for a bottle neck with cap, as shown and described.

DESCRIPTION

FIG. 1 is a front perspective view of a bottle neck with cap showing our new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The even-length broken lines immediately adjacent to the shaded area define the bounds of the claimed design and form no part thereof. The uneven-length broken lines showing the remainder of the bottle neck with cap represent unclaimed subject matter and form no part of the claimed design.
